UNITED STATES PATENT OFFICE.

JOHN H. BLUMENSTEIN, OF LA GRANDE, OREGON.

BLASTING-CARTRIDGE.

1,263,366.

Specification of Letters Patent. Patented Apr. 23, 1918.

Application filed July 5, 1917. Serial No. 178,823.

To all whom it may concern:

Be it known that I, JOHN H. BLUMENSTEIN, a citizen of the United States, and resident of La Grande, in the county of 5 Union and State of Oregon, have invented certain new and useful Improvements in Blasting-Cartridges, of which the following is a specification.

This invention relates to improvements in 10 explosive devices; the principal object of the invention being to provide a blasting cartridge so formed as to permit the ready driving or forcing of the same into a substance to the proper depth and angle there- 15 in, and upon charging, exploded, thus, demolishing or removing the substance.

It is a more specific object of my invention to provide a blasting cartridge having a substance penetrating portion adapted to 20 facilitate embedding of the same in a substance to be blasted this penetrating portion being formed to prevent the turning of the cartridge during embedding thereof and the deflecting of the same from its 25 course, and also the turning thereof when sections used in embedding the cartridge are removed.

Other and equally important objects of 30 the invention reside in the provision of a device of the character mentioned with a view to compactness, and in which the number of parts are few, the construction simple, the cost of production small, and efficiency and operation high.

35 Other objects will be in part obvious and in part pointed out hereinafter.

In the accompanying drawings wherein is shown one of the various possible embodiments of my invention:

40 Figure 1 is a perspective of the improved blasting cartridge;

Fig. 2 is a vertical section therethrough; and

Fig. 3 is a transverse section through the 45 substance penetrating portion.

Similar reference characters refer to similar parts throughout the several views of the drawings.

Certain aims and features of this invention will be more readily understood if the 50 following facts be borne in mind:

In order that the full force of an explosive might be rendered effective, it is well known that the charge must necessarily 55 be securely confined and that space between the same and the substance to be effective

must also be eliminated, thereby avoiding the forming of air cushions about the charge and materially retarding the spending of its force; also, the accurate placing of the 60 charge. Therefore, if the explosive be properly confined and placed in a substance free of air cushions, means being provided for causing the proper placing of the cartridge, the full force of the same will be spent upon 65 said substance. The above are among the dominant aims of this invention, and are, among other attained in a construction of the nature of that hereinafter described.

Having more particular reference to the 70 drawings, 1 designates a tubular body or container, the same being formed of metal or other suitable material and having one of its ends closed and pointed as at 2. It is to be noted, that the pointed portion 75 2 of the tubular body is substantially square and due to the flattened sides thereof the tubular body will be accurately directed when driven into a substance, that is, the flattened sides preventing the deflecting or 80 deviating of the same from its course as it is forced into and through the substance to be blasted.

As shown in Fig. 2, the pointed portion is 85 formed on the tubular body by mashing the end thereof with a hammer or other suitable instrument, or by suitable compressing devices commonly known to the art.

If desired, the open or remaining end of the tubular body may be internally or externally threaded, external threads being shown and designated by the numeral 3, for the purpose of convenience. By providing the open end of the body with screw threads, it will be readily understood that other sections similar to the tubular body may be 90 joined thereto or a suitable implement may be turned into engagement with the same when it is desired to force the same into a substance to be blasted. Furthermore, to 100 prevent distorting the open end of the tubular body, a protecting cap having a complementary screw shank, not shown, may be and preferably is turned into engagement with the screw threaded portion 3 of said 105 body or into engagement with the outermost ends of such sections as may be engaged with the body 1.

In operation, the tubular body 1 is forced 110 or driven into a substance to be blasted and when properly positioned therein is filled with an explosive charge, the charge being prop-

erly tamped therein. Due to the perfectly smooth inner surface of the body 1, it will be appreciated that particles of the charge will be prevented from adhering to its sides, and 5 as a consequence, premature explosions avoided. With the explosive charge properly tamped in the body 1 ignition means, such as electrodes or the like are then placed into engagement with the same and the necessary spark then supplied for exploding 10 the charge. Should the blasting cartridge be used in connection with frozen substances, the pointed or penetrating portion 2 thereof may be heated to the desired degree and 15 then embedded in the substance; sufficient time being allotted before the placing of the

explosive charge therein, in order that the penetrating portion may be cooled.

Manifestly, the construction shown is capable of considerable modification and such modification as is within the scope of my claim, I consider within the spirit of my invention.

I claim:

A blasting cartridge constructed from a 25 tubular cylindrical body having one end pointed by distorting the same and formed with flattened sides, the upper portion of said body being screw threaded.

In testimony whereof, I affix my signature hereto.

JOHN H. BLUMENSTEIN.
